VENETIAN BLINDS

Anna Horak, Berwyn, Ill.

Application August 23, 1955, Serial No. 530,028

6 Claims. (Cl. 160—172)

My invention relates to certain new and useful improvements in Venetian blinds.

An object of my invention is the provision in a Venetian blind of a plurality of slats which are mounted in a substantially vertical plane for horizontal movement and for rotation about a vertical axis.

Another and equally important object of the invention is to provide a Venetian blind of the construction hereinafter set forth which will be smooth and simple in operation and easily maintained for cleanliness; a Venetian blind in which the slats may be rotated about their vertical axes through a 360° circle and in any desired partially open or closed position.

Another object of this invention is to provide a Venetian blind in which the slats are arranged in substantially vertical position in a manner such that the blind may be used for windows, doors, room dividers, as well as other openings.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view of the Venetian blind embodying my invention;

Fig. 2 is a top plan view of the same;

Fig. 3 is a fragmentary front elevational view of the same;

Fig. 4 is a sectional detail view taken substantially on line 4—4 of Fig. 3;

Fig. 5 is a sectional detail view taken substantially on line 5—5 of Fig. 2;

Fig. 6 is a fragmentary perspective view of a Venetian blind slat together with certain of its operating mechanism;

Fig. 7 is a fragmentary sectional detail view showing adjacent slats of the blind in closed position but with the blind not being fully transversely extended; and

Fig. 8 is a fragmentary sectional detail view similar to Fig. 4 but showing the parts thereof in partially retracted position.

The several objects of my invention are accomplished by the preferred form of construction shown in the accompanying drawings. In this connection a head structure is indicated at 10. This head structure comprises a back plate 11 and side plates 12 secured together in any suitable manner. The side plates 12 are adapted to be attached in any suitable manner to the adjacent side walls of the window or door casing. The free edge portions of the side plates 12 are connected together by a transversely extending bar 13. Within the head structure 10 is a horizontally extending plate 14. Formed in this plate 14 in aligned relation with respect to each other are elongated slots 15.

Mounted for movement relative to the plate 14 are op-

2

positely disposed extendible arms 16 each comprising a plurality of cross-bars 17 interconnected together in the fashion of a lazy tong. Each of such arms 16 at each point where adjacent bars 17 cross, carries a depending sleeve 18 positioned through openings 19 formed in the bars 17 and having a flat head 20 by means of which the sleeves are supported from the arms 16. The end sleeves indicated at 21 each carry a threaded nut 22 which provides a suitable connection between the adjacent ends of the arms 16 and the plate 14 (Fig. 3). The end sleeves 23 of the sleeves 18 are fixed to the plate 14 in any suitable manner. The sleeves 18 project downwardly from the arms 16 through the slots 15 and are guided by such slots in their extended and retracted movements.

15 The extension and retraction of the arms is accomplished by an operating cord 24 of any suitable material. This operating cord passes through a guide loop 25 carried by a partition 26 provided in the head structure 10. The cord 24 is connected to the free ends of the arms 16 by clips 27 (Fig. 2). The cord extends from the loop 25 through guide tubes 28 carried by a plate 29 provided by the head structure 10.

The end portions 30 of the cord 24 extend down along one side of the Venetian blind within convenient reach of the operator.

25 Secured to each of the sleeves 18 by means of a hook 31 is an elongated bar 32 having a thread formed body portion 33, the threads of each being relatively long. These bars 32 each have their long end portions provided with hooks 34 adapted for hooked engagement with a slat 35 by insertion through a slot 36. Formed in the lower end portion of each of the slats 35 is an opening 37 through which a hook 38 of a connecting wire 39 is projected. The end of this wire 39 is projected through an opening 40 formed in a clip 41 secured in any suitable manner to a flexible tape 42. On the wire 39 is a head 43 which prevents the wire from becoming detached from the clip 41. On the tape 42 is arranged a clip for each one of the Venetian blind slats. These clips are preferably formed of suitable metal. The tape 42 is flexible for reasons hereinafter set forth. The tape is divided into two sections 44 and 45. The adjacent ends of the tape sections 44 and 45 are detachably connected together by a hook and eye construction 46.

35 40 45 The opposite end portions of the tape sections by means of a similar hook and eye construction 47 are connected to plates 48 which are adapted to be secured to the adjacent face of the window frame or door with which my improved Venetian blind is used.

50 Secured to the plate at opposite ends thereof is a bar 49, in each of which is rotatably journaled a depending rotatable thread bearing stud shaft 49.

55 Fixed to each of these stud shafts in substantially the same plane is a sprocket gear 50. The sprocket gears 50 are connected together by a sprocket chain 51.

An operating cord 52 is connected to the sprocket chain 51 by means of clips 53. The cord 52 loops around a guide plate 54 carried by the plate 12. The opposite end portions 55 of the operating cord 52 pass through 60 a guide structure 56 carried by the adjacent plate 12. These end portions 55 extend along the Venetian blind at one side thereof within easy reach of the operator.

65 As hereinbefore indicated, the Venetian blind slats are supported by the structure hereinbefore described in substantially vertical spaced relation with respect to each other. When the arms 16 are in their extreme extended position as shown in Fig. 2, the Venetian blind slats 35 will be evenly spaced from each other. The slats may be moved to open position by retracting the arms 16. This is accomplished by pulling on the operating cord 24, which by virtue of its connection with the free end portions of the arms by means of the clips 27, functions

when pulled in one direction to retract the arms and when pulled in the opposite direction, to expand the same. By this arrangement, from a vertical center line with respect to the opening within which the Venetian blind is mounted, the slats 35 may be moved from opposite sides of such line into full or partially open position as desired. The closing or partial closing of the Venetian blind slats is accomplished by manipulating the operating cord 52. When one end portion of the operating cord 52 is pulled, the sprocket gears 50 will be rotated to rotate the stud shafts 49. These stud shafts 49 thread through blocks 56 fixedly mounted in opposite end portions of a horizontally extending bar 57. This bar 57 is channel-shaped in cross-section as best seen in Fig. 6, and is provided with a longitudinally extending slot 58 through which work the thread bearing portions 33 of the bars 32. Consequently, when the stud shafts 49 are rotated in one direction, say for example to the left as viewed in Fig. 3, the bar 57 will be extended downwardly. As the bar 57 moves downwardly, it acts upon the thread bearing portions 33 of the bars 32, rotating the same in a counter-clockwise direction, thus to open the slats 35 to full or partially open position. By rotating the stud shafts 49 in an opposite direction, the bar 57 will move upwardly and as it moves upwardly it will operate upon the thread bearing portions 33 of the bars 32 and rotate the slats in a clockwise direction to full or partially closed position. It will be noted that when the slats are moved from opposite sides of a central vertical line between the plates 12, the ends of the tape sections 44 and 45 are disconnected by unhooking the hook and eye connection 46 to permit the tape section to move in the direction of movement of the Venetian blind slats.

The Venetian blind slats may be formed in any desirable shape or material and may be of any color.

From the foregoing description it will be apparent that I have provided a Venetian blind construction wherein the slats thereof may be smoothly and easily adjusted with respect to each other to suit the desire of the operator. As the slats of the blind are supported in a vertical position and are arranged so that both sides of the slats may be exposed to the operator, it is apparent that cleaning of the slats becomes a minor problem. It will also be apparent that because of their vertical position, dust and dirt and other debris is not likely to accumulate on the slats as is the case where the slats of a Venetian blind are supported in a horizontal position.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A Venetian blind comprising a plurality of vertically disposed slats, a head structure for said slats including a horizontally extending plate having an interrupted slot formed therein, a pair of spaced apart extendible arms carried by and above said plate, a plurality of sleeves carried by said arms and projecting through each portion of said slot with each sleeve having an enlarged head portion for engagement with one side of said arm, there being one sleeve for each of said slats, means for connecting said slats to said sleeves, an operating cord fixedly connected to each of said arms for moving said arms over said plate and said sleeves carried thereby through said slots in opposite direction through a horizontal plane, a thread bearing stud shaft at each end of said plate and supported thereby for rotation about its long axis, horizontally disposed sprocket wheels carried by said shafts below and in spaced relation to said plate, a flexible chain for operatively connecting said wheels together for si-

multaneous rotation, an operating cord connected to said chain for moving said chain over said wheels to rotate the same, an actuating bar threadably connected to said shafts in a substantially horizontal plane below and in spaced parallel relation to said plate and moveable in a vertical plane with respect thereto when said shafts are rotated, said connecting means including hook elements for removably connecting said slats to said sleeves with one of said elements providing a threadable connection with said bar whereby vertical movement of said bar transmits a rotatable movement to said hook element and said slats.

2. A Venetian blind comprising a plurality of vertically disposed slats, a head structure for said slats including a horizontally extending plate having an interrupted slot formed therein, a pair of spaced apart extendible arms carried by and above said plate, a plurality of sleeves carried by said arms and projecting through each portion of said slot with each sleeve having an enlarged head portion for engagement with one side of said arm, there being one sleeve for each of said slats, means for connecting said slats to said sleeves, means fixedly connected to each of said arms for moving said arms over said plate and said sleeves carried thereby through said slots in opposite direction through a horizontal plane, a thread bearing stud shaft at each end of said plate and supported thereby for rotation about its long axis, horizontally disposed sprocket wheels carried by said shafts below and in spaced relation to said plate, a flexible chain for operatively connecting said wheels together for simultaneous rotation, means connected to said chain for moving said chain over said wheels to rotate the same, an actuating bar threadably connected to said shafts in a substantially horizontal plane below and in spaced parallel relation to said plate and moveable in a vertical plane with respect thereto when said shafts are rotated, said connecting means including hook elements for removably connecting said slats to said sleeves with one of said elements providing a threadable connection with said bar whereby vertical movement of said bar transmits a rotatable movement to said hook element and said slats.

3. A Venetian blind comprising a plurality of vertically disposed slats, a head structure for said slats including a horizontally extending plate having an interrupted slot formed therein, a pair of spaced apart extendible arms carried by and above said plate, with opposite ends of each of said arms fixed to said plate at either end of said interrupted slot, a plurality of sleeves carried by said arms and projecting through each portion of said slot with each sleeve having an enlarged head portion for engagement with one side of said arm, there being one sleeve for each of said slats, means for connecting said slats to said sleeves, an operating cord fixedly connected to each of said arms for moving said arms over said plate and said sleeves carried thereby through said slots in opposite directions through a horizontal plane, a thread bearing stud shaft at each end of said plate and supported thereby for rotation about its long axis, horizontally disposed sprocket wheels carried by said shafts below and in spaced relation to said plate, a flexible chain for operatively connecting said wheels together for simultaneous rotation, an operating cord connected to said chain for moving said chain over said wheels to rotate the same, an actuating bar threadably connected to said shafts in a substantially horizontal plane below and in spaced parallel relation to said plate and moveable in a vertical plane with respect thereto when said shafts are rotated, said connecting means including a hook element carried by and freely journaled through said sleeves and adapted for rotatable movement relative thereto, a connecting bar having at one end a clip for removable connection to said slats and having at its opposite end a removable connection to said hook element, said connecting bar having a threadable connection with said bar whereby vertical movement of said bar transmits a

rotatable movement to said hook element and said slats.

4. A Venetian blind comprising a plurality of vertically disposed slats, a head structure for said slats including a horizontally extending plate having an interrupted slot formed therein, a pair of spaced apart extendible arms carried by and above said plate, with opposite ends of each of said arms fixed to said plate at either end of said interrupted slot, a plurality of sleeves carried by said arms and projecting through each portion of said slot with each sleeve having an enlarged head portion for engagement with one side of said arm, there being one sleeve for each of said slats, means for connecting said slats to said sleeves, means fixedly connected to each of said arms for moving said arms over said plate and said sleeves carried thereby through said slots in opposite direction through a horizontal plane, a thread bearing stud shaft at each end of said plate and supported thereby for rotation about its long axis, horizontally disposed sprocket wheels carried by said shafts below and in spaced relation to said plate, a flexible chain for operatively connecting said wheels together for simultaneous rotation, means connected to said chain for moving said chain over said wheels to rotate the same, an actuating bar threadably connected to said shafts in a substantially horizontal plane below and in spaced parallel relation to said plate and moveable in a vertical plane with respect thereto when said shafts are rotated, said bar having formed throughout its longitudinal length the slot corresponding to and in spaced parallel relation to the interrupted slot formed in said plate, said connecting means including a hook element carried by and freely journaled through said sleeves and adapted for rotatable movement relative thereto, a connecting bar having at one end a clip for removable connection to said slots and having at its opposite end a removable connection to said hook element, said connecting bar having a threadable connection with said bar whereby vertical movement of said bar transmits a rotatable movement to said hook element and said slats.

5. A Venetian blind comprising a plurality of vertically disposed slats, a head structure for said slats including a horizontally extending plate having an interrupted slot formed therein, a pair of spaced apart extendible arms carried by and above said plate, with opposite ends of each of said arms fixed to said plate at either end of

said interrupted slot, a plurality of sleeves carried by said arms and projecting through each portion of said slot with each sleeve having an enlarged head portion for engagement with one side of said arm, there being one sleeve for each of said slats, means for connecting said slats to said sleeves, means fixedly connected to each of said arms for moving said arms over said plate and said sleeves carried thereby through said slots in opposite direction through a horizontal plane, a thread bearing stud shaft at each end of said plate and supported thereby for rotation about its long axis, horizontally disposed sprocket wheels carried by said shafts below and in spaced relation to said plate, a flexible chain for operatively connecting said wheels together for simultaneous rotation, means connected to said chain for moving said chain over said wheels to rotate the same, an actuating bar threadably connected to said shafts in a substantially horizontal plane below and in spaced parallel relation to said plate and moveable in a vertical plane with respect thereto when said shafts are rotated, said bar having formed throughout its longitudinal length the slot corresponding to and in spaced parallel relation to the interrupted slot formed in said plate, said connecting means including a hook element carried by and freely journaled through said sleeves and adapted for rotatable movement relative thereto, a connecting bar having at one end a clip for removable connection to said slots and having at its opposite end a removable connection to said hook element, said connecting bar having a threadable connection with said bar whereby vertical movement of said bar transmits a rotatable movement to said hook element and said slats.

6. A Venetian blind as defined by claim 5 wherein said head structure provides at opposite ends thereof guiding structures for maintaining said operating cords in spaced apart parallel relation with respect to each other within said head structure and for disposing said cords therefrom on either side of said Venetian blind.
